(57) **CLAIM**

The ornamental design for a license plate frame with football helmet and face mask, as shown and described.

DESCRIPTION

FIG. 1 is a front perspective view of a license plate frame with football helmet and face mask according to the present invention, showing the frame attached to a vehicle and holding a license plate.

FIG. 2 is another front perspective view thereof.

FIG. 3 is a front elevation view thereof.

FIG. 4 is a right side elevation view thereof, the left side elevation view being a mirror image thereof.

FIG. 5 is a top view thereof.

FIG. 6 is a bottom view thereof; and,

FIG. 7 is a rear elevation view thereof.

The broken line showing is for the purpose of illustrating environmental subject matter and forms no part of the claimed design.

1 Claim, 6 Drawing Sheets
